CABLE ASSEMBLY FOR A WAVE SENSOR

Patrick M. Taiani, Halifax, Nova Scotia, Canada, assignor to Nova Scotia Research Foundation, Dartmouth, Nova Scotia, Canada

Filed May 13, 1971, Ser. No. 150,866

Term of patent 14 years

Int. Cl. D13—03

U.S. Cl. D26—1 A

FIG. 1 is a side view of the cable assembly for a wave sensor, showing my new design.

FIG. 2 is a sectional view taken along line 2—2 of FIG. 1.

The cable assembly for a wave sensor is shown broken away intermediate its ends in FIG. 1 to indicate indeterminate length.

I claim:

The ornamental design for a cable assembly for a wave sensor, as shown.
